UNITED STATES PATENT OFFICE.

EDWARD HENEL, OF ELIZABETH, NEW JERSEY.

DESIGN FOR A POISON-BOTTLE.

51,593.

Specification for Design.

Patented Dec. 18, 1917.

Application filed October 25, 1917. Serial No. 198,540. Term of patent 14 years.

To all whom it may concern:

Be it known that I, EDWARD HENEL, a citizen of the United States, residing at Elizabeth, county of Union, and State of New Jersey, have invented a new, original, and ornamental Design for a Poison-Bottle, of which the following is a specification, reference being had to the accompanying drawing, in which—

The figure is a perspective view of a poison bottle, embodying my new design.

I claim:—

The ornamental design for a poison bottle, as shown.

EDWARD HENEL.

Witnesses:

GUSTAVE C. MARX,
GEORGE STANKE.
